UNITED STATES PATENT OFFICE.

OSCAR W. MUELLER, OF CINCINNATI, OHIO, ASSIGNOR TO THE MUELLER MACHINE TOOL COMPANY, OF CINCINNATI, OHIO, A CORPORATION OF OHIO.

SAFETY MEANS FOR DRILLING MACHINES.

Application filed March 5, 1923. Serial No. 622,806.

To all whom it may concern:

Be it known that I, OSCAR W. MUELLER, a citizen of the United States, residing at Cincinnati, in the county of Hamilton and 5 State of Ohio, have invented certain new and useful Improvements in Safety Means for Drilling Machines, of which the following is a specification.

My invention relates to safety means for 10 drilling machines, especially to drilling machines of the radial type, for drilling metal.

In drilling machines of the character mentioned it is customary to provide means whereby the drill-arm is adjustable up and 15 down on a support, usually a column, and means for clamping the drill-arm in adjusted positions after adjustment. Power means are employed for adjusting the drill-arm to elevation, so arranged that the driving 20 train may be interrupted or an operating element thereof placed in neutral position, corresponding with the rest position of the drill-arm, or connections may be made in the driving train for raising the drill-arm 25 or for lowering the same.

If the drill-arm be in clamped relation and attempt be made to connect the driving relation for up or down adjustment of the drill-arm, breakage is likely to occur in 30 the driving train or one or more of the members concerned in the adjustment to elevation of the drill-arm.

It is the object of my invention, therefore, to provide novel means whereby unclamped relation of the drill-arm must be 35 obtained before the driving relation in the adjusting train of power is completed, in order that adjustment of the drill-arm shall not be initiated prior to unclamped relation thereof.

It is the object of my invention, further, to provide an operating part which is employed for operating the clamping means as well as for operating the adjusting part in 45 the driving mechanism for elevational positioning of the drill-arm; further, to provide means whereby the operating part is locked to an operated member of the clamping means during clamped relation of the clamping means; further, to provide an interchangeable operating part and mating means therefor on the movable member of the clamping means and on the movable member of the adjusting means so arranged that employment of a given operating part for actu-

ation in both the clamping means and in the adjusting means is assured; further, to provide distinctive connecting or key-hole and key means between the operating part and the movable parts respectively of the clamping means and the adjusting means; and, further, to provide automatic locking means between the operating part and the locking mechanism. 60

The invention will be further readily understood from the following description and claims, and from the drawings, in which latter:

Fig. 1 is a side elevation of a drilling machine embodying my invention, partly 65 broken away.

Fig. 2 is a plan view of the same, partly broken away.

Fig. 3 is a horizontal section of the same, taken on the line 3-3 of Fig. 1, partly 75 broken away.

Fig. 4 is a detail of the same, taken in section on the line 4-4 of Fig. 1.

Fig. 5 is a side elevation, showing the clamping arm in clamped relation in full 80 lines and in unclamped relation in dotted lines, the connecting means between the operating part and the clamping mechanism being shown in central axial section on the line 5-5 of Fig. 2. 85

Fig. 6 is a cross-section of the same, taken in the plane of the line 6-6 of Fig. 5.

Fig. 7 is a cross-section of the same, taken in the plane of the line 7-7 of Fig. 5.

Fig. 8 is an axial section of a detail, taken 90 on the line 8-8 of Fig. 4, showing the operating arm connected with the operated member of the adjusting means for adjusting the drill-arm to elevation; and,

Fig. 9 is a cross-section of the same, taken 95 in the plane of the line 9-9 of Fig. 8.

Fig. 10 is an enlarged side elevation of a detail, partly in section on the line 5-5 of Fig. 2.

Fig. 11 is a bottom view of a detail of 100 the same.

In the present exemplification of my invention, the drilling machine comprises a base 21, from which a column 22 extends in fixed relation. A drill-arm 24 extends laterally from the column, and is shown as a radial drill-arm provided with a bearing 25 received about the column, and rotatable on the column. 105

The drill-arm is provided with guide-

along which a slide 27 is adjustable in any usual manner. The slide supports a drill-spindle 28, rotated in any usual manner on 5 the slide, and arranged to carry a drill 29. Suitable means are provided for rotating the drill-spindle in either direction, permitting the same to be non-rotative, and for adjusting the same axially on the slide.

10 The drill-arm is adjustable in suitable manner up and down on the column for adjusting the elevation of the arm and of the drill supported thereby, to place the same in proper relation to the work, which is 15 supported on the base or on a super-structure mounted on the base or in other suitable manner.

I have exemplified this adjustment as accomplished by means of a screw-rod 31, 20 which is threaded in a nut 32, fixed axially in the drill-arm, as by being secured in a socket 33 in the drill-arm, the nut in this instance being exemplified as non-rotative, and the screw-rod as rotative, for providing the desired relative rotative movement 25 between the screw-rod and the nut in order to effect the adjustment to elevation of the drill-arm.

The lower end of the screw-rod is provided with a journal which has a bearing 35 in the column. The upper end of the screw-rod is journaled in a bearing 36 in a top-plate 37 of the column, and has a double width gear 38 fixed thereto. An upright shaft 41 is suitably journaled in the column, and is suitably driven, and has a pinion 42 and a gear 43 fixed thereto. The pinion 42 meshes with a gear 44 journaled on a stud-shaft 45 fixed to the top 40 plate 37. A gear 46 is journaled on a stud-shaft 47 fixed to the top plate 37 and meshes with the gear 44. The gear 46 meshes with a gear 48 fixed to an upright shaft 49, by means of which the drill-spindle is driven 45 by suitable and well-known mechanism.

In this train of gearing, the gears 43 and 44 rotate in opposite directions. A quadrant 51 is journaled about the axis of the upright screw-rod 31 and has thereon pinions 52, 53, suitably journaled on stud shafts 54 and 55 on said quadrant. The pinions 52, 53, mesh with the gear 38 fixed to the upper end of the screw-rod.

Means are provided for swinging the 55 quadrant so as to place the pinion 52 in mesh with the gear 44 or the pinion 53 in mesh with the gear 43. When the pinion 52 is in mesh with the gear 44, rotation of the screw-rod is caused in one direction, 60 for instance, to raise the drill-arm. When the pinion 53 is in mesh with the gear 43, the screw-rod 31 is rotated in the opposite direction, for instance, for lowering the drill-arm. When the pinions 52, 53, are in 65 neutral position with relation to the gears

ing to a rest-position in elevation of the drill-arm.

The swinging movements of the quadrant are shown accomplished by means of an upright rocker-rod 61, which is journaled in a bearing 62 at the lower end of the column and a bearing 63 in the upper plate 37. The upper end of the upright rod has a pinion 64 fast thereon, which meshes with 75 a segment-gear 65 on the quadrant.

Neutral relation in said driving connection for operating the upright screw-rod is preferably aided automatically by means of a pin 67, fixed in the top-plate 37, and having socket-pieces 68, 69, bearing thereagainst. These socket-pieces have axial movement in bearings 70, 71, on the quadrant. Springs 72, 73, are received in the respective socket-pieces, the outer ends of the springs bearing against the adjusting screws 74, 75, adjustable in the outer threaded ends of the bores of said bearings.

The rocking of the upright rocker-rod for effecting driving connection in the train of 90 gearing for operating the upright screw-rod in either direction is accomplished by manual means in manner to be presently described.

When the drill-arm has been adjusted to elevation, it is clamped to the column, for instance, by forming its bearing 25 as a clamp-bearing, having a split 81 therein. Clamp-screws 82, 83, are provided, respectively journaled in cheeks 84, 85, at the respective sides of the split. Nuts 86, 87, are threaded over the threaded ends of the bolts. These nuts have lugs 88, 89, extending therefrom, with which a link 90 is articulated at 91, 92. The bolts are arranged to be fixed in the cheeks 84 by means of set-bolts 93. Turning of the nuts in clamping direction causes approach between the cheeks at the opposite sides of the split for clamping the split-bearing about the column, by causing approach between the heads of the bolts at one side of the cheeks and the nuts thereof at the other side of the cheeks. The rotative position of the bolts in the cheeks affects the clamping position of the nuts, and the range and location of clamping movement of the operating part for effecting clamping and unclamping of the drill-arm.

I have preferred to show a plurality of 120 the clamping bolts and nuts, interconnected for combined movement, although it will be readily understood that other clamping means may be employed. I have shown one of the nuts, exemplified as the upper nut, as provided with an operated arm, which may be instanced as the operated member of the clamping means in the present exemplification of my invention. The operated arm is exemplified at 95 as extending from the 125 130

96 arranged to contact the bearing 25 of the drill-arm, for limiting movement of the nuts in unclamping direction.

5 I have exemplified the adjusting means for elevation of the drill-arm as provided with an operated part 97, shown as an arm extending from the upright rocker-rod 61, and as clamped rigidly to said rocker-rod by 10 means of a split-bearing 98 received thereabout, and a bolt 99, to clamp the split-bearing about said rod, the said bolt being journaled in one of the walls of the split in said bearing and threaded in the other of 15 said walls.

I have provided an operating part for the clamping means and for the adjusting means, so arranged that operation of either of said means by said operating part is essential, and have provided means whereby 20 said operating part is locked to the operated member of the clamping means during clamped relation in said clamping means, in order that movement of the operated member of the adjusting means may not take 25 place for either raising or lowering the drill-arm during clamped relation of the drill-arm.

The operated members, namely, the operated arm 95 of the clamping means and the operated arm 97 of the adjusting means, are sufficiently short so that the manual effort required to move the same by manual application to the operated parts themselves 30 would be too great to effect the operation of the clamping means or of the adjusting means, making it necessary to employ an operating part having connection with said operated parts in order to effect said respective movements.

The operating part exemplified is a handle 101, there being a single handle for operating both the operated arms of the clamping means and adjusting means respectively. 45 This single operating part is arranged to be operatively connected with only one of said operated parts at any one time, and I so form the connections as to make the connections between the operating part and the respective operated parts distinctive, in the 50 nature of a key-hole and key connection, so as to require the employment of the distinctive operating part provided for accomplishing movement in either the clamping means or the adjusting means.

Thus I have provided the operated arm 95 with a socket-piece 102, the wall of which is provided with a bore 103, an interfering stem 104 fixed in and extending from the 60 bottom of said bore outward centrally in said bore, forming an annular space 105 between the wall of the socket and the interfering stem, and providing an interruption 106 in said space, shown as formed by means of a pin secured in the wall of said

at the outer end of said space.

The arm 97 of the adjusting means is provided with a similar socket-piece 112, the wall of which has a bore 113, an interfering stem 114 fixed in and extending from the bottom of said bore outward centrally in said bore, forming an annular space 115 between the wall of the socket and the interfering stem, and providing an interruption 116 in said space, shown as formed by means of a pin secured in the wall of said socket and extending crosswise of said space at the outer end of said space.

The operating handle has its end formed 80 as a tube 121 provided with a lengthwise slot 122. The interfering stem 104 or 114 is received in the bore of the tube, and the obstructing pin 106 or 116 is received in the slot 122, making it necessary to have a 85 specially formed handle, instanced as a key-hole and key connection, to fit the operated parts in order to move the latter respectively.

I have further provided means whereby 90 disconnection of the operating part from the clamping means depends on the unclamped condition of said clamping means.

In the present exemplification the position of the operated arm during clamped relation 95 of the clamping means is shown in full lines in Fig. 5, instanced as a downward inclination of the arm, and the unclamped position of said arm during unclamped relation of said 100 clamping means is instanced as an upward inclination and shown in dotted lines in said figure.

The automatic locking means between the operating part and the operated part is exemplified as a gravity lock, comprising a 105 rolling gravity locking part, instanced as a ball 125, movable in a guideway 126, for convenience formed as a slot in a plug 127, located in a bearing 128, and secured in 110 said bearing by means of a pin 129. The bottom wall 130 of said slot is formed at an angle with relation to the axis of the socket. The slot is shown provided with overhanging outer walls 131 received part-way about the inner face of the ball, so as 115 to retain the ball in the slot, the ball having movement between the end walls of the slot formed by the wall of the bore of the bearing in which the plug is received.

When the pivoted operated arm 95 slants 120 downwardly from its pivot, the ball is caused to roll upon the inclined bottom wall of its groove for causing approach between the ball and the axis of the socket-piece, whereby contact is made between the ball and the 125 inner periphery of the tube of the operating handle, to lock the operating handle in the socket-piece, and prevent withdrawal of the handle throughout the clamped relation in 130 the clamping means. In this manner oper-

during such relation in the clamping means.

If it is the desire of the operator to adjust the drill-arm to elevation, he must first place 5 the clamping means in unclamping relation before he can remove the operating part from its connection with the clamping means, in order to employ it for effecting operative connection in the adjusting means.

- 10 This he does by raising the operating handle, whereby the operated arm 95 is swung about its pivot so as to be inclined upwardly, whereby the ball 125 is permitted to descend in its slot, for releasing the operating handle. In order to effect release of the operating handle, it is desirable to first 15 push the operating handle inwardly with relation to the socket-piece, in the direction of the arrow 132, permitted by the space 20 133, by which movement friction contact between the operating handle and the locking ball or member is released, whereupon the handle may be removed by pulling on the same in the direction of the arrow 134.
- 25 The operating handle may then be employed for effecting the desired movement in the train of mechanism for accomplishing the raising or lowering of the drill-arm.

When the adjustment has been perfected, 30 the operating handle is again removed from the operated part of the adjusting means, and inserted in the operated part of the clamping means, and the handle pulled down for clamping relation in the clamping 35 means, it being necessary to again clamp the drill-arm, whereby the handle is again automatically locked to the clamping mechanism, again necessitating release in the clamping mechanism for employment of 40 the handle for adjusting purposes. The operating part is really an interchangeable safety handle for the clamping and adjusting means, and employment of the handle for both means is necessitated by the key 45 connection between said handle and said respective operated parts.

In order to prevent sticking of the ball or gravity part in its runway, I provide a hole 135 in the wall of the runway, through 50 which gasoline or other cleansing fluid may be injected.

My improved device provides ready, economical and convenient means for insuring safety in the operation of the adjusting means for raising and lowering the drill-arm.

Having thus fully described my invention, what I claim as new, and desire to secure by Letters Patent, is:

- 60 1. In safety means for a drilling machine, the combination of a drill-arm, a member concerned in adjusting said drill-arm, a member concerned in clamping said drill-arm, an operating part for coaction with either of said members, and connecting 65 means for adjusting said drill-arm to elevation comprising a short operated arm, clamping means for said drill-arm comprising a short operated arm, a single operating handle forming an extension of said respective arms, and connecting means between said operating handle and said respective arms

second-named member arranged for automatically causing locking relation in said connecting means during clamped relation of said drill-arm and release relation in said connecting means during unclamped relation of said drill-arm. 70

2. In safety means for a drilling machine, the combination of a drill-arm, a member concerned in adjusting said drill-arm and a member concerned in clamping said drill-arm, a single operating part for both said members, and means whereby to automatically lock said operating part to said last-named member during clamped relation of 80 said drill-arm.

3. In safety means for a drilling machine, the combination of a drill-arm, a member concerned in adjusting said drill-arm, a member concerned in clamping said drill-arm, a single operating part for both said members, a keyhole and key connection between said operating part and each of said members, and means whereby to automatically lock said operating part to said 90 second-named member during clamped relation of said drill arm.

4. In safety means for a drilling machine, the combination of a drill-arm, adjusting means therefor comprising an operated member, clamping means for said drill-arm comprising an operated member, and a single operating part for said respective members, said single operating part and each of said operated parts having a combined inclosing and crossing connection between them, and said single operating part and said second named operated member having automatic locking means between them operative to lock said operating part 100 to said second named operated member during clamped relation of said clamping means. 105

5. In safety means for a drilling machine, the combination of a drill-arm, adjusting means therefor comprising an operated member, clamping means for said drill-arm comprising an operated member, a single operating part for said respective members, and automatic means for locking said operating part and said second-named operated member together during clamped relation in said clamping means and for positioning said automatic means in release relation during unclamped relation in said 115 clamping means. 120

6. In safety means for a drilling machine, the combination of a drill-arm, means for adjusting said drill-arm to elevation comprising a short operated arm, clamping means for said drill-arm comprising a short operated arm, a single operating handle forming an extension of said respective arms, and connecting means between said operating handle and said respective arms 125 130

comprising a shell, a stem therein to form an obstruction in said shell and a space between said stem and said shell, a cross-piece to form an obstruction in said space and a tubular part having a slot therein received in said space with said obstruction located in said slot.

7. In safety means for a drilling machine, the combination of a drill-arm, means for adjusting said drill-arm to elevation comprising a short operated arm, clamping means for said drill-arm comprising a short operated arm, a single operating handle forming an extension of said respective arms, connecting means between said operating handle and said respective arms comprising a shell, a stem therein to form an obstruction in said shell and a space between said stem and said shell, a cross-piece to form an obstruction in said space and a tubular part having a slot therein received in said space with said obstruction located in said slot, and an automatic lock between said handle and said second-named operated arm acting to lock said handle to said second-named arm during clamped relation in said clamping means.

8. In safety means for a drilling machine, the combination of a drill-arm, clamping means for clamping said drill-arm comprising a part arranged to be inclined in opposite directions during clamped relation and unclamped relation respectively in said clamping means, an operating part for said last-named part, and a gravity lock between said parts operative to lock said parts together during clamped relation of said first-named part.

9. In safety means for a drilling machine, the combination of a drill-arm, clamping means for clamping said drill-arm comprising a part arranged to be inclined in opposite directions during clamped relation and unclamped relation respectively in said clamping means, an operating part for said last named part, and an automatic lock for said operating part arranged to automatically lock said parts together during clamped relation in said clamping means

and to automatically place said lock in unlocking relation during unclamped relation in said clamping means.

10. In safety means for a drilling machine, the combination of a drill-arm, clamping means for clamping said drill-arm comprising an operated part arranged to be inclined in opposite directions during clamped relation and unclamped relation respectively in said clamping means, adjusting means for adjusting said drill-arm to elevation comprising an operated part, and a single operating part for said operated parts, said parts having distinctive key-hole and key connection between them, and an automatic lock for said operating part arranged to automatically lock said operating part and said first-named operated part together during clamped relation in said clamping means and to automatically place said lock in unlocking relation during unclamped relation in said clamping means.

11. In safety means for a drilling machine, the combination of a drill-arm, clamping means for clamping said drill-arm comprising a pivoted operated part arranged to be inclined oppositely at opposite sides of the horizontal plane in which its pivot is located during clamped relation and unclamped relation respectively in said clamping means, adjusting means for adjusting said drill-arm to elevation comprising an operated part, a single operating handle for said operated parts, and a rolling gravity locking part between said operating handle and said pivoted operated part arranged to lock said handle and said pivoted operated part together during clamped relation in said clamping means and to place said handle in release relation during unclamped relation in said clamping means.

In testimony whereof, I have hereunto signed my name in the presence of two subscribing witnesses.

OSCAR W. MUELLER.
